UNITED STATES PATENT OFFICE.

JOSEPH A. PETNEL, OF TROY, NEW YORK.

ELECTRIC SWITCH.

Application filed April 7, 1924. Serial No. 704,681.

This invention relates to an electric switch of a type adapted for the selective lighting of a plurality of incandescent electric lamps, or the selective energization of a plurality of other devices by an electric current.

The invention is particularly adapted for selectively lighting signal lamps of an automobile or the like.

The principal object of the invention is to provide a simple and easily actuated switch mechanism, whereby at the will of the user any selected one of a plurality of signal lamps can be lighted.

Other objects will appear in connection with the following description:

Fig. 1 of the drawings is a view in front elevation of an electric switch embodying my invention.

Fig. 2 is a similar view with the cover of the housing removed.

Fig. 3 is a rear elevation of the same.

Fig. 4 is a cross-section taken through the axis of the switch on the broken line 4—4 in Fig. 1.

Fig. 5 is a similar section taken on the broken line 5—5 in Fig. 1.

Referring to the drawings wherein the invention is shown in preferred form, 1 is the housing for the switch, having a base, 2, and a cover, 3.

The body of the housing is preferably cylindrical in form and adapted to be mounted within an aperture in the instrument-board, 4, of an automobile or the like.

The cover, 3, has a body-portion inserted within the housing body and a circumferential flange, 5, whereby the switch is secured upon the instrument-board by means of screws, 6.

I have shown three binding posts, 7, 8, and 9, extending through the base, 2, the inner ends or heads of the posts forming switch-contacts and the outer ends of the posts being connected in parallel by wires, 10, 11 and 12, with one branch, 13, of an electric circuit including a battery, 14, or other source of electrical energy.

Within the housing, 1, is a contact-plate, 15, having four bracket-arms, or legs, 16, offset as shown in Fig. 5, and mounted upon the inner side of the cover, 3, by means of screws or rivets, 17, whereby said contact-plate is adapted to be removed from or inserted within the housing by the removal from or application to the housing of the cover, 3, while at the same time the body

portion of said contact-plate is spaced away from the cover as shown in Figs. 4 and 5.

The contact-plate, 15, also has an arm, 18, in removable connection with a binding post, 19, extending through the base, 2, and connected by a wire, 20, with the other side of the circuit which includes the battery, 14.

By removing the nuts, 21, from the outer end of the binding post, 19, said post can be withdrawn from the base, 2, as the contact-plate, 15, and cover, 3, are withdrawn from the housing.

The contact-plate, 15, also has projecting therefrom, three contact-arms, 22, 23 and 24, reformed with cam-surfaces, 25, 26 and 27, respectively, the outer ends of said contact-arms being engageable respectively with the contacts, 7, 8 and 9, on the base, 2.

The plate, 15, with its contact-arms, 22, 23 and 24, is made of resilient sheet metal, permitting the outer ends of said arms to be yieldingly forced into engagement with the respective contacts on the base, while said arms withdraw from such engagement with the contacts on the base when released to their resilient force.

The cover, 3, is provided with three slots, 28, 29 and 30, which intersect one another at the center of the cover, the contact-arms, 22, 23 and 24, of the contact-plate, 15, being located opposite said slots respectively.

An actuating member, 31, is mounted upon the cover, 3, and is slidable along the respective slots, 28, 29 and 30, selectively. This actuating member is provided on its outer end with an operating handle, 32, and has on its inner end a cam-follower, 33, which is carried by said actuating member, 31, into and out of engagement selectively with the cam-surfaces, 25, 26 and 27, on the respective contact-arms, 22, 23 and 24, causing the selected contact-arm to be yieldingly forced into engagement with the respective contact 7, 8 or 9, on the base.

The end portions of the respective contact-arms, 22, 23 and 24, are preferably retroverted as shown at 34, to provide for a more yielding engagement with the respective contacts on the base.

The contact-plate, 15, is provided with a depressed seat, 35, opposite the point of intersection of the slots, 28, 29 and 30, which seat is adapted to receive the cam-follower, 33, and yieldingly retain the same at the point of intersection of said slots.

Included in circuit with the respective

wires, 10, 11 and 12, are resistances, 36, 37 and 38, which may be incandescent electric lamps or the like.

When the switch is not being used to close 5 the circuit through any of the resistances, 36, 37 or 38, the actuating member, 31, is yieldingly retained at the point of intersection of the slots, 28, 29 and 30, by engagement of its cam-follower, 33, with the depressed seat, 35, on the contact-plate, 15.

When it is desired to close the circuit through one of said resistances, the actuating member, 31, is moved along the slot opposite which is the contact-arm, 22, 23 or 24, 15 which is engageable with the contact on the base which is connected with said resistance.

As the cam-follower, 33, engages the cam-surface on the selected contact-arm, 22, 23 or 24, said arm is forced against or into engagement with the corresponding contact on the base, thereby closing the circuit through the resistance which is in connection with said contact.

Thus, if it be desired to close the circuit through the resistance, 36, the actuating member will be moved along the slot, 28; if it be desired to close the circuit through the resistance, 37, the actuating member, 31, will be moved along the slot, 29, and if it be desired to close the circuit through the resistance, 38, the actuating member will be moved along the slot, 30.

The actuating member, 31, can thus be used to close the circuit selectively through 35 any of the resistances, 36, 37 and 38, and when so used, the circuit remains broken through all of the other of said resistances.

I do not wish to be limited to the constructions shown and above described, as, for 40 certain purposes of the invention, various changes may be made in the form and arrangement of various parts of the device without departing from the spirit of the invention.

45 I have shown and described the actuating

member, 31, as slidably movable along the respective slots, 28, 29 and 30, but for certain purposes of the invention the manner in which said actuating member is movable along or within said slots is immaterial, 50 provided its cam-follower, as the cam-follower, 33, can be made to engage selectively the cam-surfaces on the circuit-closing arms of the contact-plate, 15.

For example: The actuating member, 31, 55 may, if desired, be mounted upon the cover of the housing by means of a universal joint, whereby its cam-follower can be swung into engagement with the cam-surfaces on the circuit-closing arms selectively.

60 Each of the arms, 22, 23 and 24, is preferably provided near its outer end with a depressed seat, 36, adapted to be engaged by the cam-follower, 33.

What I claim as new and desire to secure 65 by Letters Patent is:

In a device of the class described and in combination, a housing having a base, and a cover provided with a plurality of intersecting slots; a plurality of contacts mounted upon said base; a contact-member mounted within said housing, said contact member including a resilient body and a plurality of resilient arms projecting therefrom opposite the respective slots in the cover and engageable with the respective contacts on the base, each of said arms having a cam-surface, and said body being formed with a depressed seat opposite the point of intersection of said slots; and an actuating member 70 slideable along said slots selectively engageable with said depressed seat, and with the cam-surfaces on said arms to cause them to engage the respective contacts on the base, said contact-member and said contacts on the 75 base having means whereby they can be connected in an electric circuit.

80 In testimony whereof, I have hereunto set my hand this 4th day of April, 1924.

JOSEPH A. PETNEL.
